(74) Attorney, Agent, or Firm—Finnegan, Henderson, Farabow, Garrett & Dunner, LLP

(21) Appl. No.: **29/231,788**

(57) **CLAIM**

(22) Filed: **Jun. 10, 2005**

The ornamental design for a cover for a semiconductor carrier, as shown and described.

Related U.S. Application Data

DESCRIPTION

(62) Division of application No. 29/210,045, filed on Jul. 27, 2004, now Pat. No. Des. 507,248.

FIG. 1 is a top perspective view of a cover for a semiconductor carrier of our new design;

(51) LOC (8) Cl. **13-03**

FIG. 2 is a front view thereof;

(52) U.S. Cl. **D13/182**

FIG. 3 is a rear view thereof;

(58) Field of Classification Search **D13/182;**

FIG. 4 is a top view thereof;

257/666, 669, 675, 676; 324/755

FIG. 5 is a bottom view thereof;

See application file for complete search history.

FIG. 6 is a right-end view thereof; and,

FIG. 7 is a left-end view thereof.

(56) **References Cited**

The broken line showing of the environment is for illustrative purpose only and forms no part of the claimed design.
